(57) **CLAIM**

The ornamental design for a cutting torch head, as shown and described.

DESCRIPTION

FIG. 1 is a perspective of a cutting torch head of the present invention, other components of a torch being shown in broken lines and forming no part of the claimed design; FIG. 2 is a left side elevation of the cutting torch head of FIG. 1, the right side elevation being a mirror image of the left side elevation;

FIG. 3 is a top plan of the cutting torch head of FIG. 1; FIG. 4 is a bottom plan of the cutting torch head of FIG. 1; FIG. 5 is a front elevation of the cutting torch head of FIG. 1;

FIG. 6 is a back elevation of the cutting torch head of FIG. 1;

FIG. 7 is a perspective view of a cutting torch head of a second embodiment of the present invention, other components of a torch being shown in broken lines and forming no part of the claimed design;

FIG. 8 is a left side elevation of the cutting torch head of FIG. 7, the right side elevation being a mirror image of the left side elevation;

FIG. 9 is a top plan of the cutting torch head of FIG. 7; FIG. 10 is a bottom plan of the cutting torch head of FIG. 7; FIG. 11 is a front elevation of the cutting torch head of FIG. 7; and,

FIG. 12 is a back elevation of the cutting torch head of FIG. 7.

The broken lines shown in FIGS. 1 and 7 indicate structure and features which form no part of the claimed design.
